ARTICULATOR

George J. Keller, Detroit, Mich.

Application May 5, 1934, Serial No. 724,126

14 Claims. (Cl. 32—32)

This invention relates to an articulator such as is used in the making of artificial dentures.

It is the object of this invention to produce an articulator which will more accurately simulate the upper and lower human jaws in their relative movement than has been possible with articulators heretofore known.

It is also an object of this invention to produce an articulator which is simple, easily set up and operated.

In the drawings:

Fig. 1 shows a perspective view of a patient with the parallelers in position to obtain the respective positions of the right and left pivots of the lower jaw.

Fig. 2 is a perspective of the articulator.

Fig. 3 is a plan view of the articulator.

Fig. 4 is a side elevation of the articulator.

Fig. 5 is a horizontal section of the articulator taken just above the lower mandible plate showing the lower mandible plate in centric position.

Fig. 6 is a section similar to Fig. 5 showing the lower mandible plate in right and left lateral positions in the full and dotted lines respectively with the degree plates adjusted.

Fig. 7 is a section along the line 7—7 of Fig. 6.

Referring more particularly to the drawings there is shown in Fig. 1, in the dotted lines, a patient with the parallelers 1 in position to obtain the respective locations of the right and left pivots of the patient's lower jaw. Any suitable type of paralleler may be used to obtain the relative position of the pivots of the lower jaw. The paralleler 1 is used in conjunction with bite rims such as are shown in copending application Serial No. 665,276, filed April 10, 1933. The bite rims, generally designated 2, are provided with parallel prongs which engage suitable openings in the front cross bar 3 of the paralleler and are held in position by the set screws 4. The paralleler is provided with a pair of adjustable posts 5 and 6 which carry the adjustable locating pins 7 and 8. As shown, the locating pins 7 and 8 are positioned against the left and right pivots of the patient's lower jaw and the respective posts adjusted vertically relative to the parallel bars 9 and 10 and then secured in this position by the set screws 11 and 12. As brought out in the copending application, the bite rims are inserted in the patient's mouth so that, generally speaking, they fall in a plane parallel to a line extending between the wing of the nose and the auditory meatus. After the parallelers are positioned on the patient and the locating pins 7 and 8 adjusted, as above de-

scribed, the vertical distance between the locating pin 8 and the parallel bar 10 is substantially equal to the vertical distance between the right pivot of the patient's lower jaw and the junction of the upper and lower lips of the patient, that is, the line of dental engagement between the upper and lower teeth. The vertical distance between the locating pin 7 and the parallel bar 9 in a similar fashion represents the distance between the left pivot of the lower jaw and the 10 meeting line between the upper and lower lips of the patient. The right and left lateral movements of the patient's lower jaw, as well as the centric and protrusive positions of the lower jaw, are then ascertained and recorded with the bite 15 attachment of the type shown in the above mentioned copending application and according to the method therein described.

The articulator comprises a base which may be in the form of the open framework 20 and 20 a support for the maxillary and lower mandible plates which may be in the form of a U frame comprising vertical posts 21 and 22 with the connecting cross bar 23. The posts may be spot welded or otherwise suitably fixed at their base to 25 the base 20. The cross bar 23 has fixed thereon the spaced blocks 24 and 25 which carry the pin 26 which pivotally supports the upper or maxillary plate 27. Hence, the upper maxillary plate 27 has a hinge relation with the cross bar 23 but 30 may be set in horizontal, non-hinging position by the set screw 28 carried by the block 25. The lower mandible plate 29 is provided at the rear end of its side edges with the support arms 30 and 31. The support arms 30 and 31 are parallel 35 to each other and rigidly fixed perpendicularly to the lower mandible plate 29. The support arms 30 and 31 are each provided with the adjusting slots 32 which cooperate with the corresponding slots 33 in the posts 21 and 22 to permit vertical 40 adjustment of the lower mandible plate on the support posts. The arms 30 and 31 are held in adjusted position upon posts 21 and 22 by bolts 34 which pass through the slots 32 and 33 and the wing nuts 35 with suitable spacer washers between the posts and arms. The arms 30 and 31 may converge slightly inwardly from top to bottom to facilitate their swinging upon the pivot bolts 34. The posts 21 are provided with the 45 openings 36 and the arms 31 are provided with the openings 37 through which is passed the pin 38. The openings 36 and 37 are aligned with the slots 32 and 33 so that when the pin 38 is passed through these openings the arms 31 are held 50 55

truly vertical so that the lower mandible plate is positioned truly horizontal.

The lower mandible plate 29 is provided with a flat slidable plate 39 which is provided at each end with the downwardly projecting pins 40. The mandible plate 29 is likewise provided with the removable guides 41. The removable guides 41 have the downwardly projecting pins 42 which removably engage in the openings 43 in the mandible plate to removably hold the guides 41 in position. The slide plate 39 may be locked in position on the lower mandible 29 by means of the wing set screw 44 which passes through the slot 45 in the plate 39 and screws into a suitable threaded opening 46 in the lower mandible plate.

The lower mandible plate 29 may be swung about the pivot pins 34 when the pin 38 is removed by turning the threaded stud 47, the lower end of which rests on the projection 48 of the base plate 26. The threaded stud 47 is provided with a lock nut 49.

The lower mandible plate 29 is provided with degree plates for reproducing the Gothic arch of the patient which is graphically recorded on the bite attachment referred to in the above mentioned copending application. The lower mandible plate 29 is provided with a semi-circular projection 50 along its front edge and a similar projection 51 along its rear edge. The projection 50 is provided with two arcuate slots 52 and 53 having a common center 54. On the underside of the projection 50 are slidably mounted two cooperating degree plates 55 and 56, each provided with a pair of set screws 57 for holding the plates in position. Each of the plates 55 and 56 is provided with a straight edge 58 which is a radius of the circle having its center at 54. The projection 50 is provided with a semi-circular opening 59 which receives the downwardly projecting pin 40 on the slide plate 39.

The semi-circular projection 51 along the rear edge of the lower mandible plate 29 is also provided with two concentric arcuate slots 60 and 61 having a common center 62. The projection 51 is provided with an opening 63 through which the downwardly projecting pin 40 at the rear end of the slidable plate 39 projects. The projection 51 has mounted on the underside thereof the degree plates 64 and 65 which are sectors of a circle. Each degree plate 64 and 65 is provided with a straight edge 66 and 67 respectively which are radii of a common circle. The degree plates 63 and 64 are mounted on the underside of the projection 51 by the set screws 68.

The slide plate 39 is provided with a removable block 90 having inclined sides 91. The block 90 is removably secured to the top face of the plate 39 by the screws 92. When the lower bite block is cemented to the plate 39 with plaster of Paris, the block 90 becomes embedded in the plaster of Paris, and serves to anchor the lower bite block to the slide plate 39. By this arrangement, when desired, the lower bite block can be removed from the slide 39 by removing the screws 92, and when it is desired to replace the lower bite block and anchor block 90, this arrangement insures the placing of the lower bite block in exactly the same position on the plate 39 that it had prior to being removed.

The operation of the articulator is as follows: After the positions of the pivots of the lower jaw bone relative to the junction of the upper and lower lips of the patient have been registered on the paralleler, as above described, the paralleler

with the bite rims and bite blocks mounted thereon is then positioned upon the articulator, shown in Fig. 4, with the cupped ends 70 of the pins 7 and 8 engaging over the ends of the bolts 34. At this time the pin 38 is in position through openings in the arms 30 and 31 and posts 21 and 22. Cross bar 3 is set horizontally on plate 39 which is in approximately horizontal position. The wing nuts 35 are loosened and the bolts 34 adjusted vertically in the slots 32 and 33 a distance equal to that between the parallel bars 9 and 10 and the respective pins 7 and 8. The wing nuts 35 are then turned tight. The adjusting screw 71 is now turned so that the parallel bars 9 and 10 are parallel to the sliding plate 39 and necessarily the adjusting rods 5 and 6 will be perpendicular to the slidable plate 39, that is, parallel with the posts 21 and 22. The upper and lower bite blocks are now cemented to the upper maxillary plate 27 and the sliding plate 39 by any suitable material such as plaster of Paris. Thereafter the wax seal between the adjoining bite blocks is broken and the paralleler removed. This leaves the upper and lower bite blocks and respective bite rims bound to the upper maxillary 25 plate and the lower slidable plate 39.

The upper and lower bite blocks are now in centric position, that is, the position which the jaws assume when the upper and lower teeth are in normal engagement. Allowance must be made for the over-bite. To this end the set screw 44 is turned to released position so that the plate 39 is free to slide back and forth between the guides 41. At this time the remaining portion of the bite attachment, carrying the graphic recording of the Gothic arches, is secured to the bite rims, as shown in the above mentioned copending application and as indicated at 72, Fig. 5. At this time the bite plates are in centric position with the two recording pins positioned at the apex 73 of the Gothic arches. Hence, to obtain the over-bite position of the two bite blocks the pin 38 is removed and the slide plate 39 slid forwardly a distance equal to the protrusive line of the patient. This over-bite may be measured from the over-bite portion of the graphic recording on the bite attachment and the plate 39 slid forwardly an equal distance, the graduations 74 assisting one to move the plate forward the correct distance.

Another method of taking care of the over-bite is that of sliding the lower plate 39 forwardly while the recording pins of the bite attachment retrace their course from the centric position 73 to the protrusive position 75. By sliding the plate 39 forwardly and at the same time maintaining the upper and lower plates of the bite attachment in face to face contact, the lower mandible plate 29 will necessarily swing with the arms 30 and 31 about the pins 34. Thereafter the wing nuts 35 are tightened still more and the mandible plate 29 and slide plate 39 will be tilted from the horizontal practically in the same manner as the patient's lower jaw would tilt in moving from centric to protruded position. In view of the fact that the two supporting pins 34 are positioned unequal distances from the lower mandible plate 29 in a fashion similar to the positions of the pivots of the lower jaw bone of the patient, therefore the mandible plate 29 will not only be inclined from the horizontal from front to rear but will also be inclined from the horizontal as viewed from side to side depending upon whether the right or left jaw bone pivot of the patient is higher. There would be no inclination of the 75

mandible plate from side to side if the pivots of the patient's lower jaw bone were each the same vertical distance above the junction of the upper and lower lips of the patient, but this is very rare.

After the plate 39 has been set for the over-bite the next operation is that of setting the degree plates for the right and left lateral position of the lower jaw. To accomplish this the guides 41 and set screw 44 are removed from the lower mandible plate 39. The set screws 57 and 68 on the front and rear degree plates are loosened. At this time the recording pins on the bite attachment, described in the above mentioned copending application, are moved so that the recording pins 23 and 24 follow the right lateral projection graphically recorded in the Gothic arch till the pins reach the extreme right lateral position indicated at 81. Inasmuch as the lower bite plate and attachment are secured to the slideable plate 39 by the plaster of Paris this plate shifts to the right as indicated in the full lines of Fig. 6. At this time the right front degree plate 56 and the right rear degree plate 53 are moved so that the straight edge 58 of the front degree plate and the edge 67 of the rear degree plate contact with the projecting pins 40. The set screws 57 and 68 are then turned tight to hold the degree plate in this position. The setting of the left front and rear degree plates is accomplished in the same manner, namely, by moving the bite attachment and plate 39 so that the recording pins retrace the left portion of the Gothic arch till they reach the extreme left lateral projection. The degree plates are then moved into engagement with the pins 40 and secured in place by the set screws. This is illustrated in the dotted lines of Fig. 6.

The bite blocks are now in proper position upon the articulator and as soon as the bite rims and attachment are removed the technician can proceed with the setting of the teeth.

In the setting of the teeth the upper plate 27 and upper bite block remain stationary whereas the lower bite block and plate 39 are free to be shifted and simulate the centric, protrusive, and right and left lateral positions of the lower jaw. The shifting of the sliding plate 39 is facilitated inasmuch as the straight edges 58 and 66 of the degree plates which cooperate with the pins 40 to guide the movement of the sliding plate 39 are both on the lower mandible plate and are positioned on the same side of center. For example, in shifting the slide plate 39 from the right lateral position, shown in the full lines Fig. 6, to centric position the plate is slid rearwardly with the pins 40 engaging the straight edges of the right front and right rear degree plates. This arrangement makes for ease of operation of the slide plate 39 which is particularly valuable during the grinding in of the teeth.

After the teeth have been set in the trial base and tried in the patient's mouth, one may desire to raise or lower the teeth to obtain a better fit. In such case the bite may be opened or closed depending upon whether the teeth have to be raised or lowered. After it has been determined whether the teeth have to be raised or lowered, the trial bases with the teeth set therein are returned to the articulator and again set up with plaster of Paris, as above described. At this time the bite between the upper and lower teeth may be opened or closed depending upon whether the teeth are to be raised or lowered by simply swinging the lower mandible plate about its pivots 34.

Because of the suspension of the lower mandible plate on the pivot arms 30 and 31 of unequal length, the lower mandible plate in the opening or closing of the bite swings in a corresponding manner to the lower jaw of the patient. In other words, the teeth and trial bases while in the articulator and when the bite is either opened or closed to permit raising or lowering of the teeth, the teeth are in substantially the same position as they would be were they in the patient's mouth.

I claim:

1. An articulator comprising in combination a lower mandible plate and an upper maxillary plate supported above the lower mandible plate, a slideable plate mounted on, and slidably engaging, the lower mandible plate, degree plates adjustably mounted on the lower mandible plate, and means operatively connecting the slideable plate and the degree plates to guide the slideable plate during its movement.

2. An articulator comprising in combination a lower mandible plate and an upper maxillary plate supported above the lower mandible plate, a slideable plate mounted on, and slidably engaging, the lower mandible plate having spaced pins, and degree plates having straight edges adjustably mounted in spaced relation on the lower mandible plate, the straight edges of the degree plates engaging with the pins of the slideable plate to guide the slideable plate during its movement in slideable engagement with the mandible plate.

3. An articulator comprising in combination a lower mandible plate and an upper maxillary plate supported above the lower mandible plate, a slideable plate having parallel side edges mounted on the lower mandible plate, and parallel guide members carried by the lower mandible plate for engagement with the parallel side edges of the slideable plate for guiding the slideable plate while being set for over-bite.

4. An articulator comprising in combination a lower mandible plate and an upper maxillary plate supported above the lower mandible plate, a slideable plate having parallel side edges mounted on the lower mandible plate, parallel guide members carried by the lower mandible plate for engagement with the parallel side edges of the slideable plate for guiding the slideable plate while being set for over-bite, and means for locking the slideable plate in over-bite position upon the mandible plate.

5. An articulator comprising in combination a lower mandible plate and an upper maxillary plate supported above the lower mandible plate, a slideable plate having parallel side edges mounted on the lower mandible plate, parallel guide members carried by the lower mandible plate for engagement with the parallel side edges of the slideable plate for guiding the slideable plate while being set for over-bite, and a set screw for locking the slideable plate in over-bite relation with the lower mandible plate.

6. An articulator comprising a base, a support rising from the base, an upper maxillary plate mounted on the said support, a lower mandible plate pivotally mounted at spaced points upon the said support, adjustable pivots for pivotally supporting the lower mandible plate upon the said support, a slideable plate supported on the said lower mandible plate, adjustable degree plates mounted at the front and rear edges of the lower mandible plate, and means operatively connecting the slideable plate with the degree plates to guide the slideable plate during its movement.

7. An articulator comprising a base, a support rising from the base, an upper maxillary plate mounted on the said support, a lower mandible plate having a pair of supporting arms pivotally mounted at spaced points upon the said support, adjustable pivots for pivotally connecting the supporting arms with the said support, a slidable plate supported on the said lower mandible plate, adjustable degree plates mounted at opposite edges of the lower mandible plate, and means operatively connecting the slidable plate with the degree plates to guide the slidable plate during its movement.
8. An articulator comprising a base, a support rising from the base, an upper maxillary plate mounted on the said support, a lower mandible plate having a pair of supporting arms pivotally mounted at spaced points upon the said support, adjustable pivots for pivotally connecting the supporting arms with the said support, a slidable plate supported on the said lower mandible plate, and a rod arranged to pass through the support and the arms for preventing the lower mandible plate from swinging about its pivots.
9. An articulator comprising a base, a support rising from the base, an upper maxillary plate mounted on the said support, a lower mandible plate pivotally mounted at spaced points upon the said support, adjustable pivots for pivotally supporting the lower mandible plate upon the said support, a slidable plate supported on the said lower mandible plate, adjustable degree plates mounted at the front and rear edges of the lower mandible plate, means operatively connecting the slidable plate with the degree plates to guide the sliding plate during its movement, and parallel guides for engaging the side edges of the slidable plate.
10. An articulator comprising a base, a support rising from the base, an upper maxillary plate mounted on the said support, a lower mandible plate pivotally mounted at spaced points upon the said support, adjustable pivots for pivotally supporting the lower mandible plate upon the said support, a slidable plate supported on the said lower mandible plate, adjustable degree plates mounted at the front and rear edges of the lower mandible plate, means operatively connecting the slidable plate with the degree plates to guide the sliding plate during its movement, and an adjusting screw for adjusting the lower mandible plates about its pivots.
11. An articulator comprising a base, a support including a pair of posts rising from the base, an upper maxillary plate mounted on the said support, a lower mandible plate, a pair of parallel supporting arms for the lower mandible plate rising perpendicular therefrom, the said support posts and arms having corresponding slots, adjustable pivots passing through said slots for pivotally mounting the lower mandible plate upon the said support, and a slidable plate supported on the said lower mandible plate.
12. An articulator comprising a base, a support including a pair of posts rising from the base, an upper maxillary plate mounted on the said support, a lower mandible plate, a pair of parallel supporting arms for the lower mandible plate rising perpendicular therefrom, the said support posts and arms having corresponding slots, adjustable pivots passing through said slots for pivotally mounting the lower mandible plate upon the said support, a slidable plate supported on the said lower mandible plate, adjustable degree plates mounted at the front and rear edges of the lower mandible plate, and means operatively connecting the slidable plate with the degree plates to guide the sliding plate during its movement.
13. An articulator comprising in combination a lower mandible plate and an upper maxillary plate supported above the mandible plate, a plate mounted upon and in direct sliding engagement with, the lower mandible plate, degree plates for limiting the lateral and longitudinal movements of the slidable plate adjustable to vary the range of the lateral and longitudinal movements of the said slidable plate, and means operatively connecting the slidable plate and the degree plates to guide the slidable plate during its movements.
14. An articulator comprising in combination a lower mandible plate and an upper maxillary plate supported above the lower mandible plate, a shiftable plate mounted on the lower mandible plate and shiftable laterally and longitudinally in a single plane, degree plates adjustably mounted in spaced relation on the lower mandible plate, the said degree plates having straight edges in converging relation, and means carried by the shiftable plate for engagement with the converging straight edges of the degree plates to limit the range of lateral and longitudinal movement of the said plate in a single plane.

GEORGE J. KELLER.
